UNITED STATES PATENT OFFICE.

SCOTT M. SAMPSON, OF OAKDALE, CALIFORNIA.

AUTOMATIC WATER-GATE.

1,329,679.

Specification of Letters Patent.

Patented Feb. 3, 1920.

Application filed October 24, 1918. Serial No. 259,475.

To all whom it may concern:

Be it known that I, SCOTT M. SAMPSON, a citizen of the United States, residing at Oakdale, in the county of Stanislaus, State of California, have invented certain new and useful Improvements in Automatic Water-Gates; and I do declare the following to be a clear, full, and exact description of the same, reference being had to the accompanying drawings, and to the characters of reference marked thereon, which form a part of this application.

This invention relates to improvements in water gates, and particularly for a type to be used in connection with dam spillways and crests, canals, etc., where it is desired to maintain a certain head or level of water, the principal object of the invention being to produce a gate which will open and close automatically when the water level exceeds a certain height and which will close when the water level returns to normal by reason of such overflow, thereby maintaining the head of water at a predetermined level.

A further object of the invention is to provide such a gate with means whereby the same may be adjusted to open with a higher or lower head of water behind it.

A still further object is to produce a simple and inexpensive device and yet one which will be exceedingly effective for the purpose for which it is designed.

These objects, I accomplish by means of such structure and relative arrangement of the parts as will fully appear by a perusal of the following specification and claims.

On the drawings, similar characters of reference indicate corresponding parts in the several views.

Figure 1 is a view showing the gate as installed in a canal in closed position, showing the canal in cross section and viewing the gate from the upstream side thereof.

Fig. 2 is a side elevation of the same with the side wall of the canal broken away to show certain features in connection with the gate.

Fig. 3 is a fragmentary top plan view of the gate and its coacting parts.

Fig. 4 is a view similar to Fig. 2, showing the gate partly opened.

Referring now more particularly to the characters of reference on the drawings, the numeral 1 indicates the wall of the canal which is preferably of concrete and which is provided with a beam 2 transversely across the top thereof.

A gate 3 of any desired material is adapted to be positioned in the canal and to fit snugly thereacross, the edges of the gate being lined with some flexible material 4 which will prevent any water seeping between the edges of the gate and the walls of the canal.

A shaft 5 is pivoted or hinged to the outside of the gate, as at 6, which is a point somewhat to one side of the vertical center line of the gate. This shaft then crosses said center line and runs diagonally from its pivotal point to a certain distance above the gate, being maintained in position at the top of the gate by means of a collar 7 slidable on the shaft, which collar has a stud 8 thereon projecting through a slot 9 provided in a guide member 10 radial from the pivotal point 6. A nut 11 on the stud 8 clamps the collar against the guide 10 and prevents undesired lateral movement of the shaft. A collar 12 on the shaft above the collar 7 is adapted to be adjustably clamped to a guide member 13 on the beam 2 in the same manner as the collar 7; the shaft 5 being turnable in this collar 12. The shaft 5 therefore may be positioned on the gate at any point within the limits of the guides 10 and 13, for a purpose as will appear.

A ball and socket joint 14 forms the pivotal point for the lower edge of the gate, such joint being substantially in line with the shaft 5.

To the upper corner of the gate opposite to the edge to which the shaft 5 is adjacent, a cable 15 is secured. This cable passes over a pulley 16 on the edge of a cylinder 17 set in the edge of the canal and thence down into the cylinder and under a pulley 18 attached to a weight 19, which has a vertical rod 20 extending above and below the same,

the lower end of the rod having guide disks 21 thereon and the upper end being marked in any desired standard of measurement, as at 22, to form a gage. The cable 15 after leaving the pulley 18 passes over a pulley 23 at the top of the cylinder and terminates in a hook 24 adapted to catch on eyes secured to the wall of the canal, so that the cable may be pulled up short and its length adjusted to help hold the head of water at a predetermined height. The sides of the canal adjacent the edges of the gate are formed with wedge shaped recesses 25 therein, so that wedges may be driven between the wall and the gate to hold the latter when adjusting the shaft.

The weight 19 will stand at a height equal to the head wanted so that it will be half immersed, so that the full weight of the 20 same comes on the cable if the water is low, and a lesser weight if the water is high.

The principle of operation of the device is as follows:—

It will be noted that a greater percentage 25 of the area of the gate is on one side of the shaft than the other. Theoretically, as soon as the water level raises above the intersecting point of the vertical center line of the gate with the center line of the shaft (see 30 Fig. 1), the gate should start to open, owing to the fact that from that point up the water will exert greater pressure on the part of the gate presenting the greater area to one side of the shaft than the other, but practically, 35 due to unavoidable friction of the parts and the holding back effect of the cylinder weight 19, the water will normally stand about at the level of line A on Fig. 1 before any opening of the gate takes place, which 40 point is about three times the height of said intersecting point.

The amount of opening depends on the quantity of water to be passed, while set for a wanted head.

45 Should it be desired to have the gate open with a greater or lesser head of water, the shaft may be clamped in one end or the other of the members 10 and 13, thus presenting a greater or lesser area of the gate 50 on one side of the shaft to the force of the water. The bottom of the canal bed slopes down at an angle on the downstream side of the gate, as at 26 to allow of the gate's opening freely, as it assumes an angular position 55 with relation to the horizon when so opened, as shown in the dotted lines on Fig. 2.

60 It is understood of course that while I have shown a rectangular gate, I may use an inverted arch shaped gate or one with sloping sides, depending on the cross section of the canal in which it is to be placed, or as is found most desirable under varying conditions.

Also, while I have shown a leaning shaft, I may use a vertical one, which would be 65 non-adjustable and on which the gate would turn, in that case making the gate of such a shape as would present a greater part of its area to one side of the shaft than the other above a certain point, thus maintaining the 70 principle of operation of my invention.

Thus, from the foregoing description it will readily be seen that I have produced such a device as substantially fulfills the objects of the invention as set forth herein. 75

While this specification sets forth in detail the present and preferred construction of the device, still in practice, such deviations from such detail may be resorted to as do not form a departure from the spirit 80 of the invention, as defined by the appended claims.

Having thus described my invention, what I claim as new and useful and desire to secure by Letters Patent is:—

1. A water gate adapted to be positioned in a canal or in an orifice provided in a dam-crest to close the same, and being turnably mounted therein, the axis of the gate being on an angle relative to the vertical 90 center line of the gate and to one side thereof.

2. A water gate adapted to be positioned in a canal or in an orifice provided in a dam-crest to close the same, and being turnably mounted therein, the axis of the gate being on an angle relative to the vertical center line of the gate and to one side thereof, and means whereby such angle may be varied. 100

3. In a water gate adapted to be positioned in a canal or in an orifice provided in a dam-crest to close the same, a ball and socket joint between the gate and the bottom wall of the orifice in which it is seated to one side of the vertical center line of the gate, a shaft adjacent the gate pivoted to the same above said ball and socket joint and extending at an angle to the center line thereof and across the same to a bearing 110 above the gate, said shaft being substantially in alignment with the ball and socket joint, and means whereby the angle of the shaft relative to the vertical center line of the gate may be altered. 115

4. In a water gate adapted to be positioned in a canal or in an orifice provided in a dam-crest to close the same, a ball and socket joint between the gate and the bottom wall of the orifice in which it is seated 120 to one side of the vertical center line of the gate, a shaft adjacent the gate pivoted to the same above said ball and socket joint and extending at an angle to the center line thereof and across the same to a bearing 125 above the gate, said shaft being substan-

tially in alinement with the ball and socket joint, and means whereby the angle of the shaft relative to the vertical center line of the gate may be altered, such means includ-
5 ing a slotted bar mounted on the walls of the gate orifice and above the gate, said
guide being curved concentric with the
pivotal point of the gate, a collar on the
shaft, the same being turnable in the collar,
10 and a stud on the collar projecting into the

slot and having a nut thereon adapted to
impinge against the guide bar, whereby the
collar and the shaft therein may be locked
in position to the bar.

In testimony whereof I affix my signature 15
in presence of two witnesses.

SCOTT M. SAMPSON.
